UNITED STATES PATENT OFFICE.

WILLIAM HOUGHTON, OF NEW YORK, N. Y.

DOOR FOR SHIPS' BULKHEADS.

SPECIFICATION forming part of Letters Patent No. 629,790, dated August 1, 1899.

Application filed October 17, 1898. Serial No. 693,732. (No model.)

To all whom it may concern:

Be it known that I, WILLIAM HOUGHTON, a citizen of the United States, residing in the city of New York, borough of Brooklyn, State of New York, have invented certain new and useful Improvements in Doors for Ships' Bulkheads, Air-Locks, &c., of which the following is a specification.

The object of my invention is to provide a door that shall be water-tight or air-tight, or substantially so, that can be readily opened and closed, and that shall require but little space for its installation and operation. With these objects in view I provide a door frame or casing that is circular in cross-section and tapers from the top downwardly. In it I arrange a correspondingly-tapered circular door, which is a hollow chamber with a proper opening or openings to coincide or register with the openings in the door-frame. This door turns upon a vertical axis coincident with the axis of the casing. Normally when the door is closed it seats itself in its tapered socket or casing, forming a substantially water or air tight joint. When the door is partially rotated, it is caused to rise, thus passing substantially out of frictional contact with its casing and may therefore be readily turned to the desired position. In the case of doors for ships' bulkheads I also provide an arrangement by which the door, if open, will be automatically closed by the rise of water in either of the compartments which it connects. Aside from these general features my invention embodies certain details of organization, all as hereinafter described.

The interior face of the casing and the exterior face of the door may be machine-finished—that is to say, they may be turned or ground to produce the most efficient and accurate fit.

In the accompanying drawings, Figure 1 is a vertical section; Fig. 2, a transverse section therethrough on the line 2 2; Fig. 3, a similar section on the line 3 3; Fig. 4, a similar section on the line 4 4; Fig. 5, an elevation at right angles to Fig. 1, with the lower part broken away to show the rolls upon the bottom of the revolving door and the inclined tracks on the floor of the casing, upon which the rolls travel; Fig. 6, a plan view of Fig. 1; and Fig. 7, a transverse section therethrough

on the line 7 7. Figs. 8 to 14, inclusive, show a modified form of my invention, Fig. 8 being a vertical section, Fig. 9 a transverse section therethrough on the line 9 9, Fig. 10 a similar section on the line 10 10, Fig. 11 a similar section on the line 11 11, Fig. 12 a side elevation at right angles to Fig. 8 with the lower portion broken away, Fig. 13 a plan view thereof, and Fig. 14 a transverse section therethrough on the line 14 14.

I will first describe the organization shown in Figs. 1 to 7.

In Fig. 1, X represents a portion of a partition or ship's bulkhead. An opening is formed therein to which the cylindrical casing or frame is applied. This casing is shown as composed of two parts A, semicircular in cross-section and provided with flanges for attachment to the bulkhead. At the bottom their circumference is continuous, and at a suitable distance above the bottom they are formed with openings which constitute the passage-way. Above these two parts are two solid semicircular parts B, whose circumference and tops are continuous or unbroken, and which together form a closed cap for the door-frame and are provided with flanges for attachment to the bulkhead and to the parts A. This casing, throughout the area occupied by the circular door and somewhat above it, is tapered interiorly from the top downwardly. The door C is a hollow cylindrical tapering body formed with a closed bottom C' and opposite openings in its sides. It fits closely within the casing and turns upon a pivot C², that is stepped in a socket in the floor of the frame. At the top it is formed with radial arms uniting in the hub C³ at the center, and in this hub is keyed a short shaft D, that has its upper bearing in the top of the cap of the casing formed by the parts B. On the under side of the bottom of the circular door are lugs in which are journaled the shafts of conical rolls E, which run upon the circular tracks on the floor of the casing. This track or circular path F is divided into four equal parts, each of which is inclined radially to coincide with the taper of the rolls. The track is also inclined circumferentially and has two opposite low parts f, connected at each side by a rising incline f', extending through approximately a quarter of the cir-

cle to the highest point f^2 , from which it declines again to the lowest point f —that is to say, on each side of a diametric line passing through the low portions f of the track the 5 inclination of the track is upward to its highest point and then downward again, the highest points of the track being in a line at right angles to the diametric line passing through the low points f . When the rolls are upon 10 the lowest parts of these inclines, the circular door is closed and in its lowest position, as seen in sectional view Fig. 3, and is closely seated in the casing. When the door has revolved through a quarter of a revolution to 15 bring the openings coincident with the openings in the casing, the rollers travel up the inclines and lift the door from its seat in the casing and permit it to turn readily. In this position the friction and resistance to motion 20 through the shafts and gearings is sufficient to hold the door at rest in the open position with the rolls upon the highest points of the track. It is obvious that with such an organization I obtain a tightly-fitting door of great 25 strength, whose operation will not be materially impeded or interfered with by pressure upon its sides, or either of them, and that may be rotated readily with a small expenditure of power.

30 The details thus far and hereinafter described may of course be varied in many ways obvious to those skilled in the art without departing from the principles of construction and operation hereinbefore indicated.

35 The means which I have shown for controlling the operation of the door are as follows: The winch G , located at a suitable point upon one face of the bulkhead, has a driving-shaft extending through the bulkhead and 40 equipped on each end with an operating-crank. Through the medium of suitable gears a vertical shaft II may be rotated, and a beveled gear II' thereon meshes with a corresponding beveled gear on a horizontal counter-shaft II^2 , which has a beveled gear meshing with a beveled gear II^3 on a vertical shaft projecting through the top of the casing and carrying a pinion that meshes with the gear upon the shaft D , fixed in the top of the 45 cylindrical door. By the manipulation of the winch from either side of the bulkhead the door may therefore be rotated to open or close it in the manner already indicated. The beveled gears $II' II^3$ slide upon their shafts and 50 may be controlled as follows: A pivoted lever h is connected with the beveled gear II' at one end, and from its opposite end extends downwardly a rod h' , which, at its lower end, is coupled to a lever h^2 , having one end pivoted in 55 a stud or bracket on the deck below the floor-level and carrying at its opposite free end a float h^3 . The other beveled gear II^3 is connected to one end of a pivoted lever h^4 , from the opposite end of which extends downwardly a rod 60 h^5 , which, at its lower end, is pinned to a pivoted lever h^6 , similar to the lever h^2 , and having at its free end a suitable float. As seen

plainly in Fig. 5, one float is located on each side of the bulkhead, while both gears $H' H^3$ are located upon the same side of the bulkhead. The lever h^4 therefore has its free end, to which the rod h^5 is connected, on the opposite side of the bulkhead, its axis passing through a suitable bearing in the bulkhead. Normally when there is no water in the space 70 in which the floats are located the weight of the parts is sufficient to hold the beveled gears $H' H^3$ up in operative connection with the gears with which they engage. In the event, however, of water rising in the compartment 75 on either side of the bulkhead the float in that compartment rises, and the end thrust of the vertical rod connected with the lever h or h^4 causes either the gear H' or H^3 to pass out of engagement with its corresponding 80 gear. Should this condition arise, the resistance opposed to the rotation of the door is removed, and it then automatically turns, the rolls E running down the inclines of the track to the lowest points, when the door is closed 85 and seated in its socket.

In Figs. 8 to 14, inclusive, I have shown a door constructed according to my invention, which always closes the opening in which it is located. Such a door is suitable as an air-lock aboard ship where forced draft is used and also where it is desired that the divisional ships' bulkheads between large compartments shall be maintained intact. The door casing or frame is the same as that already described, 90 as is also the cylindrical door, except that it has but one opening leading into it, which in one position of the door communicates with one compartment and in the other position with the other compartment. The organization 95 otherwise is or may be the same as that already described except in the following respects: The pinions $H' H^3$ are fast in their shafts, and the counter-shaft pinion, with which II' gears, slides on a key or feather connection. Its sleeve is connected with a lever or arm M , projecting from a rock-shaft m , turning in bearings in the bulkhead and having at each end, in either side of the bulkhead, an arm or lever M' . The shaft m has a taper 105 screw m' having a correspondingly-shaped seat in the bearing, so that when the gear on the counter-shaft is thrown into mesh with II' by the manipulation of either lever M' it will so be held by the frictional binding of 110 the rock-shaft in its socket. If these two pinions be out of gear, a person in a compartment on either side of the bulkhead may throw them into gear and by means of the winch G revolve the door until its opening is turned 115 toward that compartment. He may then disengage the gears and enter the cylindrical door, within which is mounted a winch N , having a bevel-gear N' , adapted to mesh with a sliding bevel-pinion N^2 on a vertical shaft 120 O when the latter pinion is moved upward by rod n by means of a treadle pivoted on the floor of the door. The shaft O has at its upper end a spur-wheel O' , gearing with an in-

ternally-geared ring O², mounted within the cap B B of the door-casing. By this means the person within the door may revolve it until the opening is turned toward the other compartment. This requires a half-revolution of the door, and hence the rolls E E occupy the lowest portions of the track when the door is in either position.

I claim as my invention—

- 1. The combination of a tapering cylindrical door-casing having openings in its opposite sides, a correspondingly-tapered cylindrical door seated and turning within the casing and having an opening in its walls, and mechanism actuated from either side of the casing for turning the door and raising it from its seat in the casing to bring its opening opposite either opening in the casing.
- 2. The combination of a bulkhead, a tapered cylindrical door-casing forming a part thereof and having openings communicating with the respective compartments separated by the bulkhead, a correspondingly-tapered hollow cylindrical door seated and adapted to turn in the casing and having one or more openings in its walls corresponding with the openings in the casing, mechanism for turning the door, and means located on each side of the bulkhead for at will operating said mechanism.
- 3. The combination of a tapering cylindrical door-casing having openings in its opposite sides, a correspondingly-tapered cylindrical door seated and turning within the casing and having an opening in its walls, radially-arranged rolls on the bottom of the door, the inclined circular track upon which the rolls run, and mechanism actuated from either side of the door for rotating it.
- 4. The combination of a tapering cylindrical door-casing having openings in its opposite sides, a correspondingly-tapered cylin-

drical door seated and turning in the casing and having two openings in its walls, radially-arranged rolls on the bottom of the door, the inclined circular track upon which the rolls run, and mechanism actuated from either side of the casing for rotating the door to bring either its openings or its solid walls opposite the openings in the casing.

5. The combination of a tapering cylindrical door-casing having openings in its opposite sides, a correspondingly-tapered cylindrical door seated and turning within the casing and having two openings in its walls, radially-arranged rolls on the bottom of the door, the inclined circular track upon which the rolls run, and which has two low portions and two intermediate high portions connected by inclines, mechanism for rotating the door to bring its openings opposite the openings in the casing and its rolls upon the high points of the track and there holding them, and float devices for releasing the door and permitting it to descend and rotate by gravity to bring its solid walls opposite the openings in the casing.

6. The combination of a tapering cylindrical door-casing, having openings in its opposite sides, a correspondingly-tapered cylindrical door seated and turning therein and having two openings in its walls, mechanism for rotating and raising the door to bring its openings opposite the openings in the casing, and float devices for releasing the door and permitting it to descend and rotate by gravity to bring its solid walls opposite the openings in the casing.

In testimony whereof I have hereunto subscribed my name.

WILLIAM HOUGHTON.
